UNITED STATES PATENT OFFICE.

OGDEN P. LETCHWORTH, OF BUFFALO, NEW YORK.

HAME.

SPECIFICATION forming part of Letters Patent No. 311,767, dated February 3, 1885.

Application filed April 19, 1884. (No model.)

To all whom it may concern:

Be it known that I, OGDEN P. LETCHWORTH, of Buffalo, in the county of Erie and State of New York, have invented new and useful Improvements in Hames, of which the following is a specification.

This invention relates to an improvement in the construction of the hame-staple to which the hame-tug is attached, and has for its object to avoid the weakening of the body of the hame by the two holes which are ordinarily formed through the body of the hame for the reception of the two legs of the hame-staple.

15 My invention consists, to that end, of a hame staple or loop secured to the body of the hame by a connecting-plate and a single bolt or rivet, as will be hereinafter fully set forth, and pointed out in the claims.

20 In the accompanying drawings, Figure 1 is a front elevation of a portion of a hame provided with my improvements. Fig. 2 is a side elevation of the same. Fig. 3 is a vertical section at right angles to Fig. 2. Fig. 4 is a 25 horizontal section in line X X, Fig. 1. Fig. 5 is a perspective view of the hame staple or loop.

Like letters of reference denote like parts in the several figures.

30 A represents the hame, and a the metallic hame-strap secured to the outer edges of the hame.

B represents the hame staple or loop, provided at its base with flanges b b.

35 C is a clasp plate or frame extending around the front portion of the hame, and provided with an elongated opening, c, through which the staple or loop B is first inserted before the clasp or frame C is secured to the hame.

40 The plate or frame C is provided with a hook, D, which receives the breast-strap ring. The outer portion of the frame C is provided on its inner side, adjacent to the opening c, with a depression or recess, h, which fits over the base-flanges b b of the staple or loop B, and 45 firmly secures the staple or loop against the outer side of the hame when the clasp, plate, or frame C is secured in place on the hame.

50 G represents the bolt or rivet whereby the frame C and staple or loop B are secured to the hame. The rivet G is provided with a tapering head, g, which fits between the inner

tapering faces, j j, of the base-flanges b of the staple B and secures the staple to the hame. The rivet G is passed through an opening 55 formed in the hame A and the metallic hame-strap a, and through a countersunk opening, f, formed on the inner side of the frame C, and is riveted over at its inner end, whereby the parts are firmly secured to the hame. 60

If preferred, the head of the bolt G may be made to overlap the inner ends of the flanges b of the staple or loop B.

The staple or loop B and the plate C are secured to the hame by a single bolt or rivet, 65 thus avoiding the necessity of forming two bolt-holes through the body of the hame at the point where the draft is applied and where the greatest strength is required.

The frame C extends around the front side 70 of the hame in line with the bolt-hole, and compensates for the reduction in strength of the hame-body caused by the formation of the bolt-hole through the same, and forms a secure fastening for the hame staple or loop, 75 and greatly increases the strength of the hame at this point.

I claim as my invention—

1. The combination, with a hame, of a hame staple or loop, B, provided with flanges b b, a 80 frame or clasp, C, extending from the base of the hame staple or loop to the opposite side of the hame, and provided on its inner side with a depression or recess, h, and a bolt, G, whereby the said clasp or frame and the staple or 85 loop are secured to the hame, substantially as set forth.

2. The combination, with a hame, of a hame staple or loop, B, provided with base plates or flanges b b, having tapering faces j j, a 90 frame or clasp, C, extending from the base of the hame staple or loop to the opposite side of the hame, and a bolt or rivet, G, having its head fitted between the tapering faces of the flanges b, and whereby the said clasp or frame 95 and the staple or loop are secured to the hame, substantially as set forth.

In testimony whereof I have hereunto set my hand this 12th day of April, 1884.

OGDEN P. LETCHWORTH.

In presence of—

JNO. J. BONNER,
GEO. E. PITMAN.
